United States Patent Office

Des. 227,114
Patented June 5, 1973

227,114

COMPUTER TERMINAL OR THE LIKE

Charles T. Inatomi, Culver City, Calif., assignor to
TRW Data Systems, Inc., Torrance, Calif.

Filed Mar. 9, 1972, Ser. No. 233,390

Term of patent 14 years

Int. Cl. D14—02

U.S. Cl. D26—5 C

Fig. 3

Fig. 4

Fig. 5

FIG. 1 is a perspective view of a computer terminal or the like embodying my new design;

FIG. 2 is a top plan view thereof;

FIG. 3 is a bottom plan view thereof;

FIG. 4 is a right side elevational view thereof, the left side being a mirror image of the side shown; and

FIG. 5 is a rear elevational view thereof.

I claim:

The ornamental design for a computer terminal or the like, substantially as shown and described.
